(57) **CLAIM**

The ornamental design for a mirror, as shown and described.

DESCRIPTION

FIG. 1 is a perspective view of a mirror according to our new design;

FIG. 2 is a front view of the mirror of FIG. 1;

FIG. 3 is a bottom view of the mirror of FIG. 1, the top view being a mirror image thereof;

FIG. 4 is a rear view of the mirror of FIG. 1;

FIG. 5 is a right side view of the mirror of FIG. 1, the left side view being a mirror image thereof; and,

FIG. 6 is a cross-sectional view of the mirror of FIG. 1 taken at Line 6-6 of FIG. 2.

The broken lines shown in the drawings represent portions of the mirror that form no part of the claimed design.
